By Franklin D. Attorney

UNITED STATES PATENT OFFICE.

BENJAMIN M. BONILLA, OF NEW ORLEANS, LOUISIANA.

LIFE-SAVING MEANS FOR SUNKEN SHIPS.

Application filed June 24, 1926. Serial No. 118,295.

The invention relates to means for saving the life of persons on sunken ships, and has especial reference to saving the lives of the crews of submarines, and has for its object 5 the provision of a novel construction of container to receive the members of the crew of the sunken vessel, and to seal them in the vessel while being floated to the top of the water, the container including a compartment from which the air is adapted to be exhausted to create a vacuum or into which a gas lighter than air may be introduced so as to add to the buoyancy of the container, the container also having 10 rings of buoyant material such for instance as canvas or duck tubes filled with cork, these tubes adding to the buoyancy of the container, and also acting as a cushion to break the shock of the container striking 15 against piles, hulls of vessels, or other objects.

A further object of the invention is the provision of a room in the vessel in which the container hereinbefore referred to is 20 held for the emergency of the vessel sinking, provision being made for the entrance of the crew and others into the room through a door that may be closed and have a watertight fit with the wall of the room, said 25 room having a pivoted door in its top provided with means for opening the door through gearing actuated from the inside of the container.

A further object of the invention is the provision of a novel means for actuating the door for the release of the container comprising a windlass having a cable running over a crane, said windlass being actuated by gearing that is in turn actuated by means 30 of a shaft extending through a tubular opening in the side wall of the container, said shaft having a slip connection with the gearing so that it may be withdrawn within the container after the door has been opened, 35 and a cap carried on the inside of the container secured over the inner end of the tube to prevent entrance of water through the tube into the container.

The invention will be described in detail 40 hereinafter and will be found illustrated in the accompanying drawings in which—

Figure 1 is a fragmental sectional view 45 of a submarine or other vessel showing a room in the vessel and the container in position in the room, the container being shown in elevation,

Figure 2 is a horizontal sectional view on a plane indicated by the line 2—2 of Figure 1,

Figure 3 is a horizontal sectional view 60 on an enlarged scale on the line 3—3 of Figure 1, and

Figure 4 is a vertical sectional view of the container.

In the drawings similar reference characters will be used to designate corresponding parts throughout the several views.

In Figures 1 and 2 is shown the arrangements on the submarine or other vessel for saving the lives of the crew and passengers 70 on the vessel, 1 indicating the upper deck of the vessel, and 2 the inner deck, 3 indicates a water-tight room or compartment built into the vessel and as shown projecting through the upper deck 1 and adapted 75 to contain the life saving container designated generally 4, 5 indicating rests for the container 4 within the room 3. The crew and passengers enter the room 3 through an opening closed by the door 6, 7 indicating a permanent ladder leading up to the opening from the deck 2, and the members of the crew and passengers enter the container 4 through the top or cupola 8 80 9 indicating a door to close the top after 85 the crew and passengers have entered the container, 10 indicating a latch that may be of any type to hold the door in a closed position. A ladder 11 is provided within the container 4 to be used in entering and 90 leaving the container, and 12 is a bench surrounding the wall of the container for the use of the occupants.

The cupola 8 is connected with the side wall 13 by means of an inclined top 14. 95

A window 15 is located in the top 9, and other windows 16 are introduced in the inclined wall 14.

The inner side of the wall 13 is lined with 100 felt or other suitable cushioning material 17 and a cushion of the same material 18 lines the floor 19. The floor 19 also forms a partition between the compartment for the crew and passengers and a chamber 20 105 that is designed to add to the buoyancy of the container by having the air exhausted therefrom to create a vacuum, or a buoyant gas such for instance as hydrogen or helium may be introduced into the chamber, 21 indicating a nipple having a valve 22 therein 110 through which the air may be exhausted or the gases referred to introduced, 23 design-

nating a screw cap on the end of the nipple.

Surrounding the wall 13 are buoyant members 24 consisting of tubular rings of canvas or similar material designated 25 and filled 5 with cork or other buoyant material 26, and surrounding the cupola 8 is a similar ring designated 27 and made up of the same material, said rings being held in position by a net work of wire or other suitable material 10 having strands 28 extending from a ring 29 surrounding the cupola 8 above the ring 27 and down and under the bottom of the container and secured as shown at 30. Strands 28 are pressed into position by 15 means of other rings 31, 32, 33, 34, 35 and 36. 37 designates a weight in the bottom of the container that serves as a ballast to maintain the container in an upright position while floating to the top of the water 20 after being released from the vessel, as will be hereinafter described, and also to maintain the container in an upright position by floating on the surface of the water.

The room or compartment 3 is provided

25 with a hinged door 38 closing its top, and to open the door facilities are provided operated by the occupants of the container 4 which will now be described. Mounted on the deck 1 of the vessel is a crane 39 in 30 which is journaled a windlass 40 and 41 is a cable trained over pulleys 42 and 43 journaled on the crane 39 and around a pulley block 44 secured to the hinged cover 38, said cable being secured to the windlass 40 and adapted 35 to be wound thereon by means of a shaft 45 journaled on brackets 46 secured to an outer wall of the room 3 and geared as shown at 47 to the shaft of the windlass 40. 48 indicates a shaft journaled in one of the 40 walls of the room 3 and geared as shown at 49 to shaft 45, the inner end of the shaft 48 being provided with one member of a slip joint adapted to engage the other end of the slip joint on shaft 51 extending 45 through the tubular bearing 52 in the wall of the container 4 and having any preferred means for actuating the shaft secured to the inner end thereof, a hand crank 53 being used for illustration in the drawings, but 50 it will be apparent that any other means may be adopted for this purpose.

It will be apparent that when the parts are in the position shown in Figures 1 and 2, and the crew and passengers have entered 55 the container, that the occupants may lift the

cover 38 by rotating the shaft 51 from the interior of the container, and when the cover has been raised the shaft 51 will then be withdrawn within the container, and the end of the tubular bearing 52 will be closed 60 by means of a screw cap 54 that is carried in the container for this purpose so as to prevent the entrance of water into the container.

What is claimed is:—

1. In a life saving mechanism for sunken vessels, a buoyant container adapted to contain the occupants of the vessel, said container having an inclined top portion, a cupola extending centrally from said inclined top 65 and communicating with the interior of the container, a water-tight door in said cupola admitting to the interior of the container, windows in said inclined top and in the door, an air-tight compartment in the bottom of 70 said container and adapted to contain a buoyant medium, and rings of buoyant and cushioning material surrounding said container.

2. In a life saving mechanism for sunken 80 vessels, a room located in the vessel, a hinged closure for said room, a buoyant structure adapted to be located in the room and to be hermetically sealed, a door lifting device connected with the door of the room, gearing for actuating said lifting device, a shaft extending into said buoyant structure and removably connected with said gearing, means to actuate said shaft, and means to cover the bearing for the shaft when the 85 shaft is withdrawn from engaging the gearing.

3. In a life saving mechanism for sunken vessels, a water-tight room included in the vessel, a water-tight door in the top of said 90 room, said room being adapted to contain a buoyant structure, a windlass mounted on the vessel, a cable connecting said windlass with the door to open it, gearing to actuate said windlass, a shaft extended into said buoyant 95 structure and having a slip joint connection with said gearing to actuate the windlass from the interior of the structure, a tubular journal for said shaft located in the wall of the structure, said shaft being adapted to be 100 withdrawn into the buoyant structure, and a cap to close said tubular journal when the shaft is removed therefrom.

In testimony whereof I affix my signature.

BENJAMIN M. BONILLA.
